United States Patent Office

Des. 182,932
Patented May 27, 1958

182,932

WHEEL COVER

Bernard N. Smith, Oak Park, Mich., assignor to General Motors Corporation, Detroit, Mich., a corporation of Delaware

Application April 1, 1957, Serial No. 45,521

Term of patent 7 years

(Cl. D14—30)

Figure 1 is a front elevational view of a wheel cover embodying my new design.

Figure 2 is a sectional view taken on the plane indicated by line 2—2 of Figure 1.

Figure 3 is a side elevational view.

Figure 4 is a perspective view.

I claim:

The ornamental design for a wheel cover, substantially as shown.
